UNITED STATES PATENT OFFICE.

EARLE R. BURGHER, OF EAST LIVERPOOL, OHIO.

WIRE STRAIGHTENING AND PLANISHING MACHINE.

1,128,223.

Specification of Letters Patent.

Patented Feb. 9, 1915.

Application filed April 2, 1914. Serial No. 829,085.

To all whom it may concern:

Be it known that I, EARLE R. BURGHER, a citizen of the United States, residing at East Liverpool, in the county of Columbiana and State of Ohio, have invented certain new and useful Improvements in Wire Straightening and Planishing Machines; and I do hereby declare the following to be a full, clear, and exact description of the invention, such as will enable others skilled in the art to which it appertains to make and use the same.

This invention relates to metal working machinery and more particularly to a machine for straightening and planishing wire or metal rods.

The primary object of this invention is the provision of a machine for straightening and planishing metal rods or wire, which has been formed in coils or otherwise bent to destroy the straightness of the same, which machine embodies a rotatable frame carrying wire engaging convex roller dies set at an angle to each other whereby their spiral rotation will feed the wire, being straightened, through the machine; and to mount these roller dies in staggered position along the longitudinal axis of the rotatable frame to flex the rod or wire in all directions to straighten it.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters of reference designate like or corresponding parts throughout the several views, and in which:

Figure 1 is a side elevation of the improved wire straightening and planishing machine. Fig. 2 is a diagrammatic end view of the rotatable frame showing the wings formed thereupon. Fig. 3 is a vertical sectional view through the machine. Fig. 4 is a detail plan view of the roller dies and the means of mounting the same. Fig. 5 is a partial sectional view on the line 5—5 of Fig. 1 showing the rollers in elevation. Fig. 6 is a side elevation of a guide for the wire which is being straightened. Fig. 7 is a front view of the wire guide shown in Fig. 6, and Fig. 8 is a diagrammatic view

showing the angle at which the rollers are disposed during the operation of the machine.

Referring more particularly to the drawings, 1 and 2 designate pillow blocks, which have bearings formed upon their upper surfaces, in which bearings are rotatably journaled the hollow shafts 3 and 4. The hollow shafts 3 and 4 project outwardly from the ends of a frame 5, which frame has wings 6 and 7 formed upon diametrically opposite corners thereof. The wings 6 and 7 are provided with laterally extending openings 8 which receive the lugs 9. The lugs 9 are formed upon sleeves 10, which sleeves are mounted adjacent the inner faces of the wings. The sleeves 10 are rigidly held in place by means of set screws 11 which pass into the openings 8, and have their inner terminal ends threadably connected to the lugs 9 as is clearly shown in Fig. 5 of the drawings. The heads 12 of the set screws 11 are provided with annular flanges 13, which flanges abut the outer faces of the wings 6 and 7 and bind thereagainst, holding the lugs 9 securely positioned within the openings 8. The connection between the sleeves 10 and the wings 6 and 7, by the set screws 11, will permit of the sleeves being spaced horizontally to accommodate the various sizes of round metal rods or wires which it is desired to straighten. The sleeves 10 have the shanks 15 of the roller supporting tension forks 16 slidably seated therein.

The shanks 15 of the roller supporting forks 16 are externally screw threaded and provided with key-ways extending longitudinally therein in which are slidably seated the keys or feathers 18, which are carried by the sleeves 10. These keys 18 being slidably seated within the key-ways 17, will permit of the sliding adjustment of the shanks within the sleeves, but will prevent their rotation therein. The adjustment of the shanks 15 within the sleeves 10 is controlled by nuts 19, which have reduced portions 20 formed thereupon. The reduced portions 20 are inserted in the enlargements 21 of the bores of the sleeves 10.

The supporting forks 16 have their arms 22 and 23 which extend upwardly from the yoke of the fork, provided with tapering bores 24, in which are rotatably seated the frusto-conically shaped portions 25 of the bifurcated roller supports 26. The roller

supports 26 have their terminal ends which project from the smaller ends of the frusto-conically shaped portions 25, provided with screw threads upon which are mounted nuts 5 27 for securely holding the roller supporting arms within the arms 22 and 23 of the supporting fork 16. The arms 28 and 29 formed by the bifurcating of one of the ends of the roller support 26 have stub 10 shafts 30 seated in openings 31 extending therethrough. The stub shafts 30 have rollers 32 and 33 rotatably mounted thereupon between the arms 28 and 29 of the supporting arm 26. The rollers 32 and 33 form the 15 roller dies through which the wire or metallic rods being straightened pass, and by the provision of the frusto-conical portions 25 of the roller supporting arms, the angle of the axis of the rollers may be adjusted to 20 regulate the speed of travel or the speed of feeding of the wire or rods through the machine, during the operation of the latter.

In Fig. 8 of the drawings a diagrammatic view is shown illustrating the manner of mounting the rolls at an angle to the longitudinal axis of the frame 5, during the 25 operation of the machine. The rollers are disposed, during the operation of the machine, so that their central axis which is 30 designated by the dotted lines A and B respectively in Fig. 8 extends at acute angles to the central longitudinal axis of the machine which is indicated by the line C.

The tension supporting forks 16 have 35 wire or rod guides 40 secured thereto as at 41. The rod guides 40 constitute supports 42 which have the wire guides proper 43 secured to their upper ends and disposed at an angle to the vertical lines of the T supports. The wire guides proper 43 are substantially one-half of a hollow frusto-conical member and they have their small or 40 reduced ends leading to the rollers 32 and 33 as is clearly shown in Fig. 3 of the drawings.

As will be seen by reference to Fig. 1 of the drawings, the frame 5 has any desired 50 number of roller dies and the necessary parts for supporting and adjusting them connected thereto and arranged in staggered relation along the longitudinal axis of the frame.

The frame 5 has projections 45 formed thereupon and extending inwardly, being 55 disposed about the central axis of the frame and provided with bores extending therethrough, in which are seated Babbitt metal or other suitable non-abrazing sleeves 46. The sleeves 46 extend through the hollow 60 shanks 3 and 4 and are securely held in place by set screws 47 which are inserted through the projections or collars 45 and engage the surface of the sleeves adjacent their terminal ends. The pillow block 2 65 has a projection 48 formed thereupon,

which is similar in construction to the projections 45, having a set screw 49 adjustably mounted therein for engagement with the end of the sleeve 46 which is mounted within the hollow shaft 4. The hollow 70 shaft 3 extends through the pillow block 1 and has a pulley 50 mounted upon its outer end, which pulley is provided for the transmission of rotary power to the frame 5, from any suitable power supply source. 75

In the operation of the improved wire straightening and planishing machine, the metallic rod or wire to be straightened is placed upon a reel behind the feeding end of the machine. The sleeves 10 are properly 80 spaced in the horizontal slots 8, in accordance with the diameter of wire or the rod and securely held therein by the adjustment of the set screws 12. The tension supporting forks 16 are raised and locked in the 85 proper position, so that the roller dies alternately project beyond the longitudinal axis of the frame, in opposite directions, so as to spring or flex the rod or wire passing through the machine, from side to side to 90 the limit of its elasticity. The machine is then started causing the frame 5 to rotate and the end of the wire or rod to be straightened is introduced through one of the hollow bushings and directed by one of the 95 guides into the first roller die, which lifts the rod or wire from further contact with the guides. The guide next thereto, then deflects the end into the second roller die and so on successively until it passes out 100 through the hollow bushing at the delivery end of the machine. The rotary motion of the frame 5 is imparted to the rollers 32 and 33 through the contact of the convex surfaces of the rollers with the rod or wire, 105 which latter is prevented from turning by the coil on the reel and the inertia of its overhang. The axis of each pair of convex rollers in the roller dies being set at an angle to each other and in a plane parallel 110 to that of the wings, they will roll spirally around the rod or wire as the frame revolves, and their traction pushes or feeds the wire through the machine at the desired rate of speed, at the same time, the 115 contact of the hardened convex surfaces of the rotating rollers moves and planishes the rod or wire. The roller dies being staggered along the longitudinal axis of the frame, flex the rod or wire, in all directions 120 and thus straighten it. The depression between the pair of rollers forming the roller dies keeps the rod or wire from slipping off center, and any required degree of polish may be obtained by regulating the speed of 125 feed of the wire through the machine, by altering the angle at which the axis of the rollers are arranged in comparison with the longitudinal axis of the frame, the slower the feeding of the wire through the 130

machine, the higher and more efficient the polishing thereof will be.

From the foregoing description taken in connection with the accompanying drawings the advantages of the construction and of the method of operation of the improved wire straightening and planishing machine, will be readily apparent to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

20 What I claim is:—

1. In a wire straightening and planishing machine, a rotatable frame, roller supporting forks adjustably carried by said frame and arranged in staggered relation being alternately disposed upon opposite sides of the longitudinal axis of said frame, and rotatable wire engaging rollers mounted in said forks for axial adjustment with respect to each other, said rollers adapted for spiral rolling engagement with a wire upon rotation of said frame.

2. In a wire straightening and planishing machine, a rotatable frame, roller supporting forks adjustably carried by said frame and arranged in staggered relation being alternately disposed upon opposite sides of the longitudinal axis of said frame, rotatable wire engaging rollers mounted in said forks for axial adjustment with respect to each other, said rollers having convex faces and adapted for spiral rolling engagement with a wire upon rotation of the frame, and means for guiding a wire to be straightened between said rollers.

45 3. In a wire straightening and planishing machine, a rotatable frame having hollow shafts formed thereupon, and projecting outwardly from the ends of said frame, supporting bearings for said hollow shafts, said hollow shafts being provided for the passage of a wire to be straightened therethrough, roller supporting forks adjustably carried by said frame and arranged in staggered relation being alternately disposed upon the opposite sides of the longitudinal axis of said frame, rotatable wire engaging rollers mounted in said forks for angled axial adjustment with respect to each other,

said rollers having convex surfaces and adapted for spiral rolling engagement with a wire upon rotation of said frame for flexing the wire to straighten the same.

4. In a wire straightening and planishing machine, a rotatable frame, a plurality of wings formed upon said frame, sleeves adjustably connected to said wings, roller supporting forks adjustably carried by said frame and arranged in staggered relation being alternately disposed upon opposite sides of the longitudinal axis of said frame, rotatable wire engaging rollers mounted in said forks for angled axial adjustment with respect to each other, said rollers having convex faces for engagement with the wire and adapted for spiral rolling engagement with a wire upon rotation of the frame for flexing the same to straighten it.

5. In a wire straightening and planishing machine, a rotatable frame, a plurality of wings formed upon said frame, sleeves adjustably connected to said wings, roller supporting forks adjustably carried by said frame and arranged in staggered relation being alternately disposed upon opposite sides of the longitudinal axis of said frame, rotatable wire engaging rollers mounted in said forks for angled axial adjustment with respect to each other, said rollers having convex faces for engagement with the wire and adapted for spiral rolling engagement with a wire upon rotation of the frame for flexing the same to straighten it, and guides carried by said forks for receiving the wire and guiding it from one alternate set of rollers to the other.

6. In a wire straightening and planishing machine, a rotatable frame, a plurality of staggered wire engaging rollers carried by said frame, and adjustable radially of the axis of said frame, said rollers mounted for spiral rolling engagement with a wire upon rotation of said frame, for feeding the wire longitudinally through said frame, and for axial adjustment with respect to each other for regulating the speed of feeding the wire through said frame, said rollers having convex faces for planishing a wire upon spiral rolling engagement therewith, and means for guiding a wire between said rollers.

In testimony whereof I affix my signature in presence of two witnesses.
